UNITED STATES PATENT OFFICE

MOSES K. BERNSTEIN, OF SAN FRANCISCO, CALIFORNIA

DESIGN FOR A RADIO CLOCK CABINET

Application filed December 20, 1929. Serial No. 33,872. Term of patent 3½ years.

To all whom it may concern:

Be it known that I, MOSES K. BERNSTEIN, and
a citizen of the United States of America,
residing at San Francisco, in the county of
San Francisco and State of California, have
invented a new, original, and ornamental
Design for Radio Clock Cabinets, of which
the following is a specification, reference be-
ing had to the accompanying drawings, form-
ing a part thereof.

Figure 1 is a front elevation of my design,

and

Figure 2 is a side elevation of the same.

I claim:—

The ornamental design for a radio clock
cabinet substantially as shown.

MOSES K. BERNSTEIN.
